UNITED STATES PATENT OFFICE

LOUIS LUDWIG, OF PHILADELPHIA, PENNSYLVANIA

SHUTTLE AND BOBBIN

Application filed May 31, 1930. Serial No. 458,146.

This invention relates to a shuttle and bobbin arrangement, the general object of the invention being to provide a shuttle having means therein for supporting a plurality of 5 bobbins, with the thread or yarn so arranged on the bobbins that when one bobbin is empty, the thread or yarn will be drawn from another bobbin and this will continue until all the bobbins are empty, so that it is not 10 necessary to stop the loom to replace a bobbin at frequent intervals, as is the case where but one bobbin is used.

Another object of the invention is to provide means for stopping the loom when the 15 thread from the last bobbin has been removed therefrom.

This invention also consists in certain other features of construction and in the combination and arrangement of the several 20 parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a top plan view, with parts in 30 section, of the improved shuttle, with the bobbins therein.

Figure 2 is a side view.

Figure 3 is a section on line 3—3 of Figure 1.

Figure 4 is a fragmentary plan view, with parts in section.

Figure 5 is a section on line 5—5 of Figure 4.

Figure 6 is a section on line 6—6 of Figure 4.

Figure 7 is a section on line 7—7 of Figure 6.

Figure 8 is a section on line 8—8 of Figure 4.

Figure 9 is a perspective view of one of the latch means.

Figure 10 is a perspective view of the rear end of a bobbin.

In these drawings, the letter A indicates 50 a shuttle which is of sufficient length to be

divided into a number of bobbin chambers 1, so that a plurality of bobbins B can be carried by the shuttle. The partitions 2 which divide the shuttle into the bobbin chambers are each formed with a centrally located 55 hole through which a tube 3 passes, this tube being suitably held in the hole and has a part projecting beyond the partition so that this projecting part will enter the enlarged part of the bore 4 of the bobbin which is 60 arranged in the base thereof. Each of said partitions also forms a support for the latch member 8 for engaging the annular groove 9 in the base of the bobbin. Each latch member is of angle shape in cross section, with 65 the pins 10 carried by one limb of the member, these pins passing into the holes 11 extending vertically through the partition and a spring 12 is located on each pin and engages 70 a part of the partition and a projection on the pin so that these springs tend to hold the latch member in latching engagement with the bobbin. The base of each bobbin is formed with a number of diagonally arranged 75 holes or passages 13 therein which have their inner ends communicating with the bore adjacent the tube 3 so that the thread passing through the tube can pass forwardly at an angle through one of these passages and then be wrapped around the bobbin in the 80 usual manner.

A spool 14 is rotatably arranged in a chamber 15 formed in one end of the shuttle in rear of the last bobbin to be unwound and a pair of contacts 16 is placed in the chamber and is insulated from the shuttle and these contacts are electrically connected with any suitable form of stop means for the loom. The spool carries a bridge piece 17 which, when the spool is moved to a certain position, will bridge the contacts 16 and thus complete the circuit to the stopping device so that the loom will be stopped. One end of the thread or yarn is fastened to the spool after the same is placed in a position with its bridging piece 17 out of engagement with the contacts, as shown in Figures 1 and 4. The thread or yarn is then passed through the first tube 3 and through one of the passages 13 in the first bobbin and is then 100

wrapped around said bobbin. The thread or 3
yarn is then passed through the second tube
5 and through a passage 13 of the second
bobbin and after being wrapped around the
second bobbin, is then carried to the third
bobbin and so on until all the bobbins are
filled. The yarn passes from the last bobbin
10 through a hole 18 formed in a partition 19
into the chamber 20 in which the tension
brush 21 is located and after passing through
said brush, the yarn is passed through a hole
22 into an elongated chamber 23 formed at
15 one side of the shuttle and the yarn passes
from the chamber through a hole 24 arranged
at the center of the shuttle.

From the foregoing it will be seen that the
yarn is first drawn from the bobbin located
adjacent the friction brush and then when
20 this bobbin is empty, the yarn is drawn from
the next bobbin and so on until all the bobbins
25 are empty. As soon as the first bobbin
is empty, or that bobbin which is next to the
spool 14, the pull of the yarn will cause the
spool to turn so that the bridge piece 17 will
bridge the contacts, thus completing the cir-
cuit to the stopping device so that the loom
will be stopped. The latch means are then
raised so that the empty bobbins can be re-
moved and full ones substituted therefor.
30 By passing the yarn through the chamber
23, there is no danger of the yarn leaving
the shuttle being interfered with by the yarn
leaving the bobbin.

Thus I have provided simple means where-
35 by the loom can be run for a long time with-
out stopping the same to renew the bobbins.

It is thought from the foregoing descrip-
tion that the advantages and novel features
40 of the invention will be readily apparent.

40 It is to be understood that changes may be
made in the construction and in the combina-
tion and arrangement of the several parts,
provided that such changes fall within the
scope of the appended claims.

45 What I claim is:—

1. A shuttle of the class described com-
prising a plurality of bobbins arranged in
50 the shuttle, the yarn on the bobbins being
connected together in a continuous manner
whereby when one bobbin is empty, the yarn
will be drawn from the next bobbin, and a cir-
cuit closer for a loom stopping device in the
55 shuttle and operated by the yarn when the
last bobbin is empty.

55 2. A shuttle of the class described com-
prising a number of bobbin chambers, a bob-
bin in each chamber, means whereby the yarn
from one bobbin passes to the next bobbin so
60 that the yarn is continuous and a circuit
closer for a loom stopping device in the
shuttle and operated by the yarn when the last
bobbin is empty.

65 3. A shuttle having a number of partitions
therein dividing the same into a number of
bobbin chambers, a tubular member carried

by each partition and entering a part of each
bobbin, each bobbin having a diagonally ar-
ranged passage in its base leading from the
tubular member to the exterior of the bobbin
whereby yarn can pass through each tubular
70 member and the passage and be wrapped
around the bobbin, a circuit closer for a loom
stopping device in the shuttle and operated
by the yarn when the last bobbin is empty,
and latch means carried by each partition for
75 holding a bobbin in position.

4. A shuttle having a number of partitions
therein dividing the same into a number of
bobbin chambers, a tubular member carried
80 by each partition and entering a part of each
bobbin, each bobbin having a diagonally ar-
ranged passage in its base leading from the
tubular member to the exterior of the
bobbin whereby yarn can pass through each
85 tubular member and the passage and be
wrapped around the bobbin, latch means
carried by each partition for holding a bob-
bin in position, a circuit closer for a loom
stopping device in the shuttle in rear of the
90 last bobbin and to which the yarn is con-
nected, whereby the yarn will move the closer
to a position for closing a circuit of the loom
stopping device when the last bobbin is
empty.

5. A shuttle having a number of partitions
therein dividing the same into a number of
bobbin chambers, a tubular member carried
100 by each partition and entering a part of each
bobbin, each bobbin having a diagonally ar-
ranged passage in its base leading from the
tubular member to the exterior of the bobbin
whereby yarn can pass through each tubular
105 member and the passage and be wrapped
around the bobbin, latch means carried
by each partition for holding a bobbin in
position, one side of the shuttle having a
passage through which the yarn passes from
110 the first bobbin, a circuit closer for a loom
stopping device in the shuttle and operated
by the yarn when the last bobbin is empty,
and friction means carried by the shuttle and
engaging the yarn after it leaves the first
115 bobbin.

In testimony whereof I affix my signature.
LOUIS LUDWIG.
